CLAIM

The ornamental design for display screen or portion thereof with animated graphical user interface for converting control into code editor, as shown and described.

DESCRIPTION

FIG. 1 is a front view of a display screen or portion thereof with animated graphical user interface for converting control into code editor showing a first image of a sequence of the animated graphical user interface.

FIG. 2 is a second image thereof;

FIG. 3 is a third image thereof;

FIG. 4 is a fourth image thereof;

FIG. 5 is a fifth image thereof;

FIG. 6 is a sixth image thereof; and,

FIG. 7 is a seventh image thereof.

The long dash-short dash lines show the boundary of the claimed design and the display screen or portion thereof and form no part of the claimed design. The short dash-short dash lines and the areas within the short dash-short dash lines form no part of the claimed design. The broken line text forms no part of the claimed design.

The appearance of the animated images transitions sequentially between the images shown in FIGS. 1-7. The process or period in which one image transitions to another forms no part of the claimed design.

1 Claim, 4 Drawing Sheets
